L. W. LUCE

DEVICE FOR SUPPORTING WALLS OF A TILE GAME

Filed May 15, 1923

UNITED STATES PATENT OFFICE.

LUCY W. LUCE, OF BROOKLYN, NEW YORK.

DEVICE FOR SUPPORTING WALLS OF A TILE GAME.

Application filed May 15, 1923. Serial No. 639,063.

To all whom it may concern:

Be it known that I, LUCY W. LUCE, a citizen of the United States, residing at 116 Remsen Street, Brooklyn, in the county 5 of Kings and State of New York, have invented a new and useful Improvement in a Device for Supporting Walls of a Tile Game, of which the following is a specification.

10 The invention has to do with tile games, such as the game of mah jongg, and the object is to aid in the building of the wall and in supporting the pieces taken from the wall to form the "hands" or sets of the 15 players. The invention is, in part, an improvement upon and within the invention of my prior application Serial No. 635,955 filed May 1, 1923.

20 In the accompanying drawings forming part hereof and illustrating a preferred embodiment of this invention:

25 Fig. 1 is a plan view of the apparatus assembled to form a frame of definite proportions, within and against which to build the tile wall, a portion of which is indicated by broken lines;

30 Fig. 2 is a rear elevation on a larger scale of one of the members, with a portion broken out because of limitation of space;

35 Fig. 3 is a vertical transverse section on the line 3—3 of Fig. 2, indicating the position of one of the tiles in the trough-rack; and

40 Fig. 4 is an elevation of one corner of the frame.

The frame of Fig. 1 is formed by interlocking the four separable members 1, one of which is shown in greater detail in Figs. 2 and 3.

45 Each of these members comprises a trough-like, outwardly facing rack 2, having a base, a back and ends, and open at the top and front, the ends being preferably formed by plates 3 applied to the ends of the

50 body, which may be of wood. The inner bottom face 4 of the rack inclines downward and rearward, and the inner back face 5 inclines upward and rearward, so that the tiles are supported in an inclined position

55 represented at α in Fig. 3, rendering them convenient to read and insuring against their toppling forward out of the trough. The length of the rack is so proportioned that, with the largest size of tiles on sale,

55 there is sufficient room for the player to draw his full set of tiles and to provide ad-

ditional space for slipping the tiles back and forth to assort them in suits, and the tiles can not tumble over and become exposed to other players. The closed ends likewise 60 keep the tiles from slipping off endwise.

Projecting from the ends of the troughs and even with the backs are interlocking terminals 6, 6^a formed by flat bar pieces 7, 7^a secured to the body by screws 8. In some 65 cases the bar part of the member might be continuous, but it is advantageous to divide it in two pieces, as shown, set in a groove 9 in the back face of the body or intermediate part, wherein they can be shifted longitudinally to increase or diminish the distance between the interlocks.

As in the prior application aforesaid, the 75 interlocks are formed by slotting the projecting end portions half way from opposite edges, one interlock having a single slot 10, while the other has two slots 10^a, 10^b, the two slots being spaced apart by a distance 80 corresponding approximately to the length of a tile, so that the wall may be built either with or without extra tile pieces. One of the ends, that which is provided with the downwardly facing slot, is also provided with a scalloped projection 11 forming a 85 handle for lifting this end to disengage the lock.

The movability of the interlocks of each member relatively to each other by sliding them on the body enables the frame members to be set for different makes of tiles, 90 which vary somewhat in composition and also slightly in proportions. This flexibility is best secured by forming the bar pieces with longitudinal slots 12, having countersunk edges, to accommodate the flush-head 95 screws 8. By loosening these screws the bar pieces 7, 7^a, or one of them, can be appropriately shifted, and the screws can then be tightened to hold the parts in the desired relation.

100 What I claim as new is:

1. An apparatus for use in a tile game, comprising a set of members consisting of racks adapted to receive the "hands" of tiles of the respective players, with projecting interlocking terminals on the racks to form an enclosure of definite proportions, the racks and terminals being constructed to form continuous surfaces against which to build the sides of a wall of tiles.

110 2. A member of an apparatus as set forth in the foregoing claim, further character-

ized by being constituted of a trough part and a flat bar part affording the terminals, the back of the trough part being grooved and the bar part being set flush into the 5 groove, substantially as described.

3. An apparatus for use in a tile game comprising a set of racks with interlocking terminals, the several members containing provision for increasing or diminishing the 10 distances between their terminals, substantially as described.

4. An apparatus for use in building the walls of a tile game, comprising a set of bars or members to form an enclosure of 15 definite proportions within and against which to build a wall of tiles, the said members being formed with interlocking separable ends and having provision in each member for increasing or diminishing the 20 distance between such ends, substantially as described.

5. An apparatus for use in building the walls of a tile game, comprising a set of bars or members to form an enclosure of definite proportions within and against 25 which to build a wall of tiles, each of said members being formed at opposite ends, respectively, with a single slotted and a double slotted interlock, and having provision for increasing or diminishing the distance be- 30 tween the interlocks.

6. An apparatus for use in building the walls of a tile game, comprising a set of bars or members to form an enclosure of definite proportions within and against which to 35 build the wall of tiles, each of said members comprising an intermediate part and two end parts adapted to be fixed at different positions lengthwise with reference to the intermediate part, the end parts having 40 interlocks.

LUCY W. LUCE.
